JAMES E. SULLIVAN, OF CINCINNATI, OHIO, ASSIGNOR TO THE SULLIVAN PRINTING WORKS COMPANY, OF CINCINNATI, OHIO, A CORPORATION OF OHIO

SHEET DIVIDING AND COMPILING MECHANISM

Application filed July 25, 1930. Serial No. 470,694.

The present invention relates to a compiling mechanism and has for an object the provision of means whereby a plurality of forms printed on a single sheet may be cut apart and then compiled or set up in a given order and delivered in the desired groups or stacks without intermediate handling.

Another object is to provide a means whereby uniform sheets each printed with a plurality of forms are fed to a cutting device where the sheets are divided into smaller sheets which are deposited upon a conveyor having an intermittent advance synchronized with the rate of deposit of the small sheets so that after the conveyor has received a deposited sheet in superposed order at each station along the delivery line it will have properly compiled stacks of the smaller sheets for discharge at the end of its travel.

Another object of the invention is to provide a novel means to automatically arrest movement of the compiling mechanism upon failure of feed of a large sheet to the cutter mechanism, and to automatically actuate the conveyor operating means upon restoration of the feed of sheets to the cutter.

These and other objects are attained by the means described herein and disclosed in the accompanying drawings, in which:

Fig. 1 is a side elevation of the driving side of the device of the invention.

Fig. 2 is a view taken on line 2—2 of Fig. 1.
 Fig. 3 is a view taken on line 3—3 of Fig. 1.
 Fig. 4 is an enlarged view of a gripper forming a detail of the invention.
 Fig. 5 is a view taken on line 5—5 of Fig. 3.
 Fig. 6 is a view taken on line 6—6 of Fig. 5.
 Fig. 7 is a view taken on line 7—7 of Fig. 2.
 Fig. 8 is a view taken on line 8—8 of Fig. 7.
 Fig. 9 is a view taken on line 9—9 of Fig. 2.
 Fig. 10 is a view taken on line 10—10 of Fig. 9.

In the present invention there is provided a feed table 20 from which large sheets 21, each carrying across its width a plurality of printed forms 22, such as monthly calendar sheets are fed to slitting wheels or rolls, where they are taken by suitable grippers and carried thereby while the cutting takes place whereupon the grippers deposit the severed

portions upon a conveyor which has an intermittent movement equal to the width of one such severed portion. The effect of discharging a series of monthly calendar or other sheets and the intermediate shifting of the receiving conveyor effects a simple and certain compiling of the desired stack of sheets. An automatic conveyor control governed by the presence or absence of one of the large sheets at the feed guides insures a perfect compilation even though the operator or automatic sheet feeder employed may fail.

A suitable standard or frame 23 carries a suitable driving gear 24 which in this embodiment is mounted on the shaft of an electric motor 25. The entire device is actuated from this power source by preference. Gear 24 drives gear 26 fixed on shaft 27 which in turn has crank 28 secured thereto. A pitman 29 is pivoted to crank 28 and to a point 30 intermediate the ends of lever arm 31. This lever arm is pivoted at its end 32 upon an extension 33 of the frame 23.

The lever arm serves as a means to reciprocate the gripper carriage and to impart rotation in alternately opposite directions to the cutter shafts.

A link 34 is pivoted at its one end to lever arm 31 and at its opposite end to an end 35 of the carriage 36 which is mounted by rollers 37 to ride upon the top plane edges of rack members 38 which are fixed upon suitable extensions 39 and 40 of the frame 23. Pinions 41 are fixed on a revoluble shaft 42 journaled in the opposite sides of the carriage and mesh with the teeth 43 on the lower side of each of the racks 38. The gripper carriage is in this way power driven at each end to effect a smooth uniform reciprocating movement.

A sliding rack 44 is attached at its one end to the carriage and as it reciprocates with the carriage it moves a gear 45 fixed on an extended portion of the lower cutter shaft 46 which also carries a gear 47 meshing with gear 48 on upper cutter shaft 49. A hold down wheel 50 on an extension of the upper shaft 49, keeps the rack 44 in mesh with gear 45 so that both cutter shafts are power driven alternately in opposite directions as the car-

riage and its associated rack 44 are reciprocated by the lever arm 31.

The shafts 46 and 49 are provided with a suitable number of pairs of complementary cutter or slitter discs 51 which are removable and adjustable so that a sheet such as 21 may be divided into a desired number of smaller sheets 22.

The cutting or sheet slitting is effected by gripping the large sheet 21 with a pair of gripping fingers 52 and 53 (see Fig. 4) between each pair of slitter discs 51, said fingers reaching between and beyond the shafts 46 and 49 and between adjacent sets of slitter discs so that the sheet is gripped by the grippers in advance of the slitters and is drawn between the slitters to be divided by them. The gripper fingers 52 and 53 retain their hold on the divided portion or smaller sheet 22 as the grippers are moved away from the slitters and are finally opened to deposit the individual smaller sheets 22 in their original side by side (but now separated) relation upon a conveyor which has a stepwise transverse movement relative to the initial line of movement of the sheets or portions 22 equal to the space between adjacent pairs of slitters.

Before describing the structure, actuation and control of the conveyor and grippers, it will be well to fully understand the operation and effect of the structure thus far described.

Sheets 21 fed manually or by an automatic sheet feeder are positioned against suitable guides on the feed table 20 just in advance of the slitter discs. The grippers (hereinafter more fully described) are moved by the carriage on its forward movement to reach between the shafts and the several sets of slitters to grasp the sheet 21 at a plurality of places such that each subsequently separated portion will be within a pair of gripper fingers. The grippers retain their hold on the sheet during the slitting operation which takes place as the slitters are rotated and the carriage effects its return movement away from the slitters.

The conveyor is at rest when the series of sheets or portions 22 are deposited thereon. The several sheets 22 may be the consecutive leaves of a calendar pad of twelve monthly leaves or any portion of such, or another type of pad. By depositing the severed series of leaves 22 on the conveyor, then moving the conveyor for a distance equal to the width of one leaf it will be seen that subsequently slit and deposited sheets 22 will be built upon a stack and will contain the superposed sheets in the same order or rotation as the different monthly sheets appeared on the large sheets 21. Obviously the stacks discharged from the conveyor will be incomplete until the conveyor has advanced the number of steps equal to the number of sheets 22 extending across

sheet 21. Thus if the sheet 21 contains forms for six sheets or leaves 22, the machine will discharge uniform properly compiled stacks after the sixth advance of the conveyor until the last six sheets 21 are severed. The direct deposit of the sheets 22 in the proper compilation effects an exceptional saving of time and permits the machine to operate as fast as the sheets 21 can be fed to it without danger of error or destruction of the sheets.

The gripper structure comprises a square bar 54, which may also be a continuation of the extension 35 of the carriage, and a rocking shaft 55, which shafts carry the mountings for the gripping fingers 52 and 53 respectively. The fingers 52 are each securely but adjustably mounted on bar 54 by means of a yoke piece 56 and a pair of bolts 57 which may pass through a pair of rectangular spacers 58.

The fingers 53 are each mounted on a block 59 by a pair of screws 60 which also pass through a companion block 61. The blocks 59 and 61 have between them a bore to receive shaft 55 and are additionally notched at 62 to provide a way which allows a key 63 in shaft 55 to have a limited amount of free radial movement therein. The shaft 55 has fixed thereon a cam finger 64 having an antifriction roller 65 at the end. As the carriage reciprocates it moves the cam finger beneath fixed cam 66 at one end of the frame and a movable cam 67 at the opposite end. Engagement of the roller 65 with such cams imparts partial rotary movement to shaft 55 so that key 63 may tilt the blocks 59 and 61 and raise the gripping end of finger 53 against the resistance of a spring 68 which normally retains the gripping ends of the fingers 52 and 53 in engagement.

In order to permit the gripping fingers to close upon the sheet 21 at the proper moment the movable cam 67 is pivoted at 680 and has a lug 69 projecting beyond it to provide a pivotal mounting for an operating bar 70 which depends therefrom. A rocker arm 71 is pivoted on the frame at 72 and has the operating bar pivoted to it intermediate its ends. A roller 73 on the end of arm 71 rides upon a cam wheel 74 which is mounted on shaft 27. It will be seen that an abrupt nose 75 on cam 74 will serve to lift the cam 67, which had previously served to hold the gripping fingers 52 and 53 apart, and allow the fingers to take hold of a sheet 21 positioned on feed table 20. The operating bar 70 also has a link 76 connected to bell crank 77 which carries a retiring guide 78 which is moved down out of the path of the paper 21 when the grippers close on it.

The cam 74 through operating bar 70 holds cam 67 out of operative position so that the grippers retain their hold on sheet 21 as they are moved back by the carriage, and draw the sheet between the slitters discs. Continued movement of the carriage causes the grippers to draw the now separated sheets or portions

22 transversely across the conveyor until roll 65 on finger 64 engages fixed cam 66 when the grippers open and withdraw, leaving the several sheets side by side on the conveyor. The carriage now returns allowing the grippers to repeat the operation on the next sheet 21.

The conveyor consists essentially in a pair of parallel intermittently actuated shafts 79 and 80 each carrying a suitable closely spaced series of pulleys 81 upon which conveyor belts 82 are mounted. The shafts 79 and 80 are driven in unison from a shaft 83 through miter gears 84 and 85. On the end of shaft 83 there is provided a suitable means to secure intermittent unidirectional rotation of the shaft from a reciprocating rack 86. In this embodiment this intermittent motion is attained by an overrunning clutch indicated generally at 87, (see Figs. 3, 5 and 6). This comprises a flanged disc or cup 88 fixed on shaft 83 and a free disc 89 carrying eccentric rollers 90 on studs 91 which also secure a gear 92 which meshes with rack 86. Light springs 93 urge the eccentric rollers to contact the inner periphery of the cup 88 so that when rack 86 moves in one direction disc 89 moves rollers 90 in one direction and they merely drag lightly upon cup 88. When the rack 86 moves in a reverse direction the rollers 90 immediately bind upon the cup 88 and impart to shaft 83 the movement of gear 92. An extension 930 bolted on or integral with the frame of the machine serves as a bearing for the rack 86 and a journal for shaft 83 and the hub 94 of cup 88. An arcuate piece 95 may be used to form a split bearing for the latter.

The rack 86 has a hinged connection at 96 with a pitman 97 which has an accurately adjustable eccentric mounting on disc 98 secured for rotation with hub 106. The eccentric mounting (see Figs. 9 and 10) comprises a pair of inverted L-shaped members 99, conveniently made of two flat strips, which serve to slidably support an inverted T-shaped block 100 for adjustment diametrically across disc 98. The block carries an upright stud 101 to which the pitman 97 is attached. An adjusting screw 102 is rotatably mounted at its opposite ends in end pieces 103 and the threads engage in a threaded bore in block 100. The end 105 of adjusting screw 102 is adapted to receive a wrench or other tool whereby the block, or more specifically the stud 101 is moved to the desired distance from the center of the disc 98 to regulate the stroke of the pitman 97 and the rack 86 connected thereto. This structure makes possible an exact intermittent advance of the conveyor belts for each turn of the disc 98 which make one revolution for each complete reciprocation of the gripper carriage.

From the foregoing it will be noted that while the carriage is advancing to move the fingers forward toward the table 20, the con-

veyor moves one step forward thus advancing the previously deposited cut sheets 22 a distance equal to the width of one of such sheets 22. When the grippers reach and grip a new sheet 21, the conveyor comes to rest and remains so while the sheet 21 is drawn through the slitters and the resulting cut sheets 22 are moved onto the conveyor. In the case of calendar pads the several months will be printed across the large sheet 21 and the same kind of sheet 22 (e. g. Jan., Feb., Mar., etc.) will always be grasped by the same grippers and deposited in the same spot relative to the top of the machine but the stepwise movement of the conveyor is such that each previously deposited cut sheet or form 22 will have the adjacent sheet or form of a succeeding sheet 21 deposited thereon.

If the conveyor were to continue its stepwise operation and the feed of sheet 21 should fail, the series of compiled sheets would be disorganized, thus discharging a number of incomplete stacks equal to the number of sheets 22 across the sheet 21 times the number of reciprocations of the carriage during which no feed took place. The means shown in Figs. 7 and 8 are automatically operable to stop the advance of the conveyor each and every time there is no sheet 21 in position for the grippers and to automatically actuate the conveyor moving mechanism in proper synchronism as soon as the feed of sheet 21 is resumed. This makes it impossible for an incorrectly or incompletely compiled stack of sheets 22 to be made up on the conveyor.

As shown in Fig. 7 and 8 the shaft 27 has fixed thereon a disc 107, the periphery of which provides a cam 108, and on the side of which is a dog 109 pivoted thereto on stud 110. A notched disc 111 which has the hub 106 integral therewith is freely rotatable on shaft 27 and is driven therewith whenever dog 109 seats in the notch. The dog is urged to engage the notched disc 111 by spring 112 and a cam shoulder 113 on the dog raises a lever 114 once every revolution of disc 107, by means of a roller 115 mounted on stud 116 on said arm. A pin 117 in the frame limits the downward movement of the arm 114. The device is shown in Fig. 7 in position wherein a sheet has failed to feed to position and the trip is just about to render inoperative the disc 98 and its pitman. A pivotally mounted arm 118 has a roller 119 which constantly rides on cam disc 107, dropping into the depression in the cam and rising again once each revolution of said cam. Arm 114 raises normally when the cam face 113 of the dog passes beneath the roller 115. A feeler mechanism comprising a substantially triangular plate 120 pivoted on the same stud 121 with arm 118 has a finger 122 which normally rests on pin 123 projecting from the side of arm 118 whereby a feeler 124 having a bell crank lever connection with rod 125

may rise and descend due to the pivotal connection of said rod with plate 120. The plate has an adjustable counter-balance 126 so that the action of the feeler 124 is light enough to 5 be retarded by a sheet of thin paper. A ledge 127 on the feed table 20 has a slot or aperture at 128 so that when a sheet of paper such as 21 is pushed into position against the retiring guide 78, and the feeler descends 10 thereon, the paper will preclude the plate 120 and its finger 122 from further descent and the cam shoulder 113 on dog 109 will merely raise the arm 114 without disturbing the driving relation of the dog with notched disc 15 111. If, however, there is no sheet in position on the feed table, the feeler will drop below the ledge 127 and tip the finger 122 downwardly into the path of the shoulder 129 on the end of arm 114 and offer a solid 20 resistance to movement of the arm whereupon the action of the cam face 113 on the dog will be to raise the dog from its driving relation with the notched disc against the resistance of spring 112. The notched disc 111, sleeve or 25 hub 106 and disc 98 will then stop and no further movement can be imparted to the conveyor because pitman 97 partakes of the movement of disc 98. A constantly dragging brâke B may act on disc 98 if desired. 30 The arm 118 however, continues to rise and fall due to its relation with the continuously moving disc 107. As arm 118 rises it also lifts the feeler 124 above ledge 127 to permit a subsequently fed sheet 21 to be placed in 35 position for the grippers 52-53 to reach it. As soon as the sheet is supplied the feeler rests on the sheet and the finger 122 fails to descend far enough to block the arm 114. The dog 109 snaps into driving engagement 40 with notched disc 111 so that the conveyor movement is again established in perfect synchronism.

Since all moving parts receive their power through shaft 27 and the pitman 97 can be 45 actuated only when dog 109 engages the single notch in the disc 111 there is no danger of disturbing the perfect functioning of the machine either by stopping the motor 25 or because of the failure of the feed of sheets 21.

50 The machine as a whole is compact and requires a floor space which is but little greater than the area of two of the maximum size of sheet 21 to be cut up and compiled thereby. It will be understood that the conveyor may 55 be built to extend to a greater distance in the direction of its discharge end if desired.

The number and spacing of the slitters on shafts 46 and 49 and the adjustability of the pitman 97 on disc 98 render the machine 60 adaptable to a variety of sizes of work.

What is claimed is:

1. In a device for dividing and compiling sheets the combination of a feed table, a series of cooperating slitters, a conveyor arranged 65 for intermittent movement transversely of

the cutting line of the slitters, a carriage reciprocable transversely above the conveyor, normally closed grippers mounted on the carriage and movable between adjacent slitters to grasp a sheet positioned on the feed table 70 and means to first open and then close the grippers adjacent the slitters and to again open the grippers adjacent the remote side of the conveyor for depositing the severed portions of the sheet upon the conveyor. 75

2. In a device for cutting and compiling smaller sheets from large sheets the combination of a feed table, a pair of slitter shafts disposed one above and one below the plane 80 of the forward edge of said table and parallel therewith, slitter discs on said shafts, reciprocating grippers movable between the shafts and slitters to and from the edge of the feed table and a conveyor having intermittent 85 stepwise movement and movable at each step a distance equal to the distance between the slitters parallel to and adjacent the slitter shafts for receiving the severed portions from the grippers. 90

3. In combination a series of spaced slitter discs for dividing a sheet into a plurality of uniform smaller sheets, a conveyor movable intermittently transversely to the lines of the severed edges of the sheets and movable each time a distance equal to the distance between the slitters and gripper means reciprocable over the conveyor between adjacent slitter discs and actuatable to grasp a sheet, draw it between the slitter discs and deposit the uniform smaller sheets on the conveyor in the same relation that said sheets had before severance. 95

4. The method of compiling a plurality of sets of printed forms comprising printing the several forms in the desired sequence across the width of each of a plurality of large sheets, then dividing the forms by a simultaneous series of longitudinal cuts through said large sheets, then depositing the severed forms in undisturbed side by side 100 relation upon a shiftable surface, shifting the surface laterally for a distance equal to the width of one of said severed forms and repeating all of said operations on successive sheets whereby successive stacks of assorted forms are built upon the shiftable surface, each form in each finished stack having been taken from a different one of the large sheets. 105

5. In a device of the class described the combination of a pair of vertically spaced parallel slitter shafts, spaced cooperating slitter discs on the shafts, a feed table at one side of said shaft, a conveyor at the other side of said shafts, gripper means movable in opposite directions between the shafts and over the conveyor, means to open and close the gripper means adjacent the table and to open said gripper means adjacent the remote side of the conveyor, means to impart intermittent unidirectional movement to the conveyor, 110 115 120 125 130 135 140 145 150

- each movement equal to the distance between the slitters, a feeler operative adjacent the edge of the feed table and movable below the plane of the table when no sheet is in position 5 for the grippers, means to drive the conveyor moving means, a connection between the feeler and said driving means whereby the latter is disconnected from the conveyor moving means when the feeler moves below the plane of the table, mechanism whereby the said driving relation is re-established upon resumption of feed of sheet to the grippers and means whereby the grippers are continuously reciprocated.
- 10 6. In a device of the class described the combination of a feed table, retiring guides intermittently projecting above the forward edge of the table, a conveyor, means to move the conveyor intermittently in a direction crosswise of the front of the table, continuously operating slitters disposed between the table and conveyor, each conveyor movement equal to the distance between adjacent slitters, gripper means reciprocating continuously 15 between the slitters and over the conveyor, means controlling the action of the grippers whereby a sheet positioned at the front of the table may be grasped by the grippers and drawn through the slitters and then deposited upon the conveyor, means to drive the conveyor moving means in synchronism with the advance of the grippers, a disabling mechanism for said drive means, a feeler operating at the front of the table for restraining the disabling means when it contacts a properly fed sheet and releasing the disabling means to stop the drive on the conveyor moving means upon failure of feed of a sheet, the feeler again automatically restraining the disabling means upon encountering a sheet.
- 20 7. In a device of the class described the combination of a supporting frame, a power driven shaft journalled in said frame, a pair of fixed racks supported by the frame, a carriage comprising a pair of members having fractional mounting on one side of each rack, a shaft journalled in said members and having pinions thereon meshing with the racks, a pitman actuated from the power driven shaft and operative through a lever arm for reciprocating the carriage members on their mountings, a movable rack connected to the carriage, a pair of slitter shafts, a pinion on 25 one of said slitter shafts meshing with the rack, a pair of intermeshing gears carried by said slitter shafts whereby the slitter shafts are rotated in opposite directions upon movement of the rack by said carriage, pairs of complementary slitter discs on the slitter shafts, normally closed gripper means on the carriage adapted one each to pass between and beyond said shafts and each pair of adjacent slitter discs, a feed table 30 adjacent said forward limit of movement of the grippers, retiring guides for positioning a sheet of paper to be slit within the reach of said grippers, movable means adjacent the slitter rolls for effecting opening of the grippers and subsequent release for closing the grippers upon the sheet between each adjacent pair of slitter discs, a conveyor operating transversely of the slitter discs, adjustable means for advancing the conveyor a predetermined distance during the advance of the carriage and grippers and means adjacent the return limit of the carriage for opening the grippers to release the severed sheet for deposit upon the conveyor.
- 35 8. In a control for a stepwise moving automatically compiling conveyor the combination of a feed table and guides, an apertured ledge on the table, a pivotally mounted bell crank lever comprising a feeler member movable through the aperture in the ledge in the absence of a sheet to be operated upon and sustained by said sheet when properly positioned, slitter mechanism, a gripper mechanism for grasping a sheet on the ledge and drawing it through the slitters to divide the sheet and for depositing the severed sections upon the conveyor, intermittent driving mechanism for advancing the conveyor a predetermined distance while the gripper mechanism is advancing to grasp a sheet, said mechanism being inoperative on the conveyor during deposit of the severed sections of the sheet on the conveyor, and means connected with the bell crank lever for completely disabling the conveyor moving means upon descent of the feeler through the aperture in the ledge and means whereby the feeler is automatically raised during each forward movement of the grippers, whereby the disabling mechanism may be restrained upon insertion of a sheet and the conveyor drive is automatically resumed in synchronism with the carriage movement.
- 40 9. In a device for disabling a compiling mechanism upon failure of a supply of sheets and for automatically actuating the compiling mechanism upon renewal of the feed of sheets, the combination of a power driven shaft, a disc fixed on the shaft and having a dog pivoted on the face thereof, a notched disc freely revoluble on the shaft and normally constrained to rotation with the shaft through the agency of the dog, an integral hub on the notched disc, a third disc fixed on said hub, a pitman eccentrically connected to said third disc, a pivoting arm provided with a roller intermediate its ends for encountering the dog as it rotates with the first disc whereby said arm is normally oscillated on its pivotal mounting, said arm also having a notch in the end thereof, a second arm having an end adapted to ride upon the periphery of the first disc, said periphery being cut away at one place to effect movement of the second arm about its 45

pivot, a pin on said second arm, a finger having an independent pivotal mounting on the same axis with the second arm, a pivotally mounted feeler associated with a suitable feed table and adapted to be sustained by a sheet to be operated upon and a connection between said pivotally mounted feeler and said finger whereby, upon failure of the feed of sheets the feeler may descend and move the finger into the path of the notch in the first mentioned arm whereby said arm is restrained against movement by the dog and effects an unseating of the dog in the notched disc whereby the third disc and its associated pitman are released from driving relation with the shaft.

10. In a device of the class described the combination of a pair of shafts for supporting a conveyor, miter gears on said shafts, a third shaft, miter gears on said third shaft engaging one each with the miter gears on the conveyor shafts, a pinion freely mounted on said third shaft, a reciprocating rack meshing with said pinion, an over-running clutch comprising one member fixed on the third shaft and a companion member fixed on the pinion whereby continuous movement of the rack in opposite directions serves to impart intermittent unidirectional movement of the conveyor shafts, a pitman connected at its one end to the shaft, a disc having the opposite end of the pitman eccentrically mounted thereon, continuously reciprocating gripper means for receiving sheets and depositing them on the conveyor, a feed table for said sheets, a feeler adapted to contact each sheet as the grippers advance to receive it, means controlled by the feeler for automatically disabling the pitman upon failure of a sheet on the feed table, said means comprising mechanism for intermittently lifting the feeler to restrain the disabling mechanism upon resumption of feed of sheets to the grippers.

45. In testimony whereof, I have hereunto subscribed my name this 18th day of July, 1930.

JAMES E. SULLIVAN.
